BATHROOM SCALE

Lucille Evely Hansen and Stan B. Hanssen, Northbrook,
Ill., assignors to Hanson Scale Company, a corporation
of Illinois

Application July 1, 1954, Serial No. 31,252

Term of patent 14 years

(Cl. D52—10)

FIG. 1

FIG. 2

FIG. 3

FIG. 4

Figure 1 is a top plan view of a bathroom scale, showing our new design;

Figure 2, a side elevational view;

Figure 3, an end elevational view as seen from the right in Figure 2; and

Figure 4, an end elevational view as seen from the left in Figure 2.

We claim:

The ornamental design for a bathroom scale, as shown.
